UNITED STATES PATENT OFFICE

JOSEPH BASILE, OF NEW YORK, N. Y., ASSIGNOR TO GREENPOINT METALLIC BED CO., INC., OF BROOKLYN, NEW YORK, A CORPORATION OF NEW YORK

COUCH DAY BED

Application filed January 3, 1931. Serial No. 506,341.

The present invention relates to couch day beds, otherwise known as davenports, of the type wherein there is an elevating or upwardly and downwardly movable inner mattress-supporting section and another mattress-supporting section which is pivoted to the main frame of the bed so that it may be swung from an inner position, when it presents a couch portion, to an outer position alongside and in front of the movable inner section when it presents a second mattress, so that a double day bed is provided. Some couch day beds of this type are provided with legs for supporting the pivoted bed section in using position when it is swung out, some of such legs being automatically operated and others being merely pivoted in position and are moved to upright position directly by hand. The present invention contemplates an improved operating mechanism connecting the two movable bed sections and which may be used whether automatically operated legs are provided or not.

One of the objects of the present invention, in connection with foldable or collapsible beds of the type referred to, is to provide operating mechanism, between and connecting the movable bed sections and which functions in such manner that the act of swinging the pivoted bed section in either direction causes the inner bed section to tilt downwardly from its rear edge toward its front edge to such an angle that a considerable space or throat is produced between those edge portions of the two bed sections which are the nearest to the pivots of the pivoted bed section, when they are moving between the limits of the closed and open positions of the bed. The effect of this is to prevent the binding of the operating mechanism and the crowding or squeezing of the portion or portions of the mattress or mattresses which is or are the closest to the said edge portions of the bed sections, and thereby preserve the mattress or mattresses in proper and undamaged condition.

Another object is to so construct and operate the bed sections of a bed of this type that heavier or thicker mattresses may be employed, as for example a thirty pound mat-

tress which is half again as heavy as the customary one.

A still further object is to so construct the operating mechanism and so mount the same on the main frame and the bed sections that when the bed is in closed position, the couch portion may be of such size or length as to come so close to the head and foot boards as to substantially if not entirely close up the gaps which usually intervene in beds of this type, and thereby provide obvious advantages over previous beds of this type.

Other objects are to improve in other ways the construction and operating mechanism of beds of this type and render them more salable and attractive to the users.

These being among the objects of the present invention, the same consists of certain features of construction and combinations of parts to be hereinafter described and then claimed with reference to the accompanying drawings illustrating a preferred embodiment of the invention, in which:

Figure 1 is an end elevation of the improved bed in collapsed position;

Fig. 2 is an edge view of the pivoted bed section showing the legs as folded back out of use;

Fig. 3 is a front edge view of the extended pivoted bed section showing the legs in upright position for use as in Fig. 5;

Fig. 4 is a plan of corresponding ends of the two movable bed sections showing the operating mechanism;

Fig. 5 is an end elevation of the couch day bed opened out for use as a double bed;

Fig. 6 is an end elevation of the bed showing the movable bed sections and the mechanism which connects them, in intermediate position; and

Fig. 7 is a detail sectional plan showing the guiding and lifting means for the inner bed section.

In the drawings, only one end of the bed is shown, as it will be readily understood that the mechanism at each end of the bed is of the same construction and operates in a similar manner. The stationary main frame of the bed is constructed mainly of angle metal and comprises a pair of uprights 12, 13, end

rails 14, 15 connecting one pair of uprights with the other pair of uprights, not shown of course, back rails 16, 17, and front rail 18. Such main frame is provided with a front board 19 which extends from end to end thereof and hides the mechanism behind it as well as imparts a finish to the bed. The uprights 12, 13 are provided with slots 20 which are adapted to receive lugs on head and foot pieces, only one of which is roughly indicated in the drawings.

Within the main frame there is mounted for an up or down movement an inner bed section, the frame of which includes longitudinal side rails 21, 21 which may be of angle metal and end rails 22 of similar metal, only one end rail being of course shown. The back edge of the frame 21, 22 carries at each end a guide roller 23, each roller being located for an up or down movement in a channel preferably formed by an upright 12 and associated length 24 of angle metal riveted on, although the parts 12 and 24 may be formed from one piece of channel metal. The inner bed section is raised or lowered as hereinafter described and supports spring coils 25 in well known manner and a border wire 26 and a mattress 27 which is secured to the border wire in any suitable manner.

The pivoted bed section has a frame including longitudinal side rails 28, 29 and end rails 30, all preferably of angle metal, and one of these end rails being of course not shown. Upon such frame there is rigidly mounted a cushion or upholstered couch portion 31 which contains suitable coil springs. Coil springs 32 are also carried by the frame 28, 29, 30 on the reverse side from which the portion 31 is secured and they are connected with a border wire 33 to which the mattress 34 is secured. The two mattresses 27 and 34 are preferably connected together along their adjacent longitudinal edges by a seam or a flexible connection 35, so that a folding mattress body is provided.

A rigid lug 36 projects forwardly from the upper end of front upright 13 of the main frame and a bracket 37 on the end rail of the extension bed section is connected by a pivot 38 with said lug. It is here repeated that the parts now being described as to one end of the bed are repeated at the other end of the bed, so that the duplicate mechanism at the ends of the bed will function together. Connecting the upholstered couch portion 31 with the front board 19, and extending from end to end of the bed is a valance 39 of suitable fabric, so that when the bed is closed it presents a neat and acceptable appearance. When the extension bed section is swung inwardly on its pivotal connection so as to be in the position shown in Fig. 1, that edge of the same which is away from the pivotal connection will rest upon the adjacent uprights

at each end of the bed, and the bed may then be used as a couch.

The operating mechanism which connects the two bed sections, and now to be described, is disclosed but not claimed in a previous application filed December 8, 1930, Serial No. 500,699. For this purpose the vertically movable inner section and its parts will, for convenience, be characterized by the letter A and the pivoted bed section and its parts will be characterized by the letter B.

Referring to Figs. 4, 5 and 6 lifting links 40, 41 for the inner bed section A are respectively mounted at their lower ends on pivots 42, 43 supported by the end rail 14 of the main frame. These lifting links are indicated by broken lines in Fig. 1 where the inner bed section A is in lowermost position. At their opposite ends the lifting links 40, 41 are respectively provided with inwardly projecting pins 44 and said pins enter slots 45 in the end rail 22 of the frame of the bed section A. When the links 40, 41 are moved, the said pins travel in one or the other direction in the said slots and raise or lower the inner bed section A as the case may be. During such movement the rollers 23 travel up or down in the guide channels provided for them, and maintain the bed section A for a movement in vertical direction.

Connecting links 46, 47 are provided for the bed sections A and B, link 47 operating closer to the pivotal connection 38 than does the link 46, and the link 46 being of a length greater than the link 47. The connecting link 46 is pivotally connected at one end with the lifting link 40 by means of the pivot 44, while the other end of link 46 is connected by a pivot 48 with the end rail of extension bed section B as clearly indicated in Figs. 4 and 5. Preferably the ends of the link 46 are deflected towards the pivots thereat because of the preferred location of such pivots when the bed is open. One end of the shorter connecting link 47 is connected with an intermediate portion of the lifting link 41 by a pivot 49, and the other end of the link 47 is connected by a pivot 50 with a short projecting arm 51 on the bracket 37 which is carried by the extension bed section B.

A bracket 52 extends upwardly from the end rail 15 of the main frame, as shown in Figs. 1, 5 and 6, and to this rigid bracket corresponding ends of helical extension springs 53, 54 are attached. The other end of tension spring 53 is attached to a link 55 which is hung on pivot 50 carried by the extension bed section B. The opposite end of the tension spring 54 is attached to an intermediate portion of the connecting link 47. These tension springs 53, 54 assist in closing the extension bed section B. A third helical tension spring 56 is provided so as to assist in opening out the extension bed section B, one end of said spring being attached to lift-

ing link 40 and its other end attached to a link 57 which is pivoted to the front upright 13.

Referring to the described operating mechanism it will be noted that the series of links 40, 46 is longer than the series of links 41, 47 which are located in front of them, and that these two series of links are located in front of the guide channel of the uprights 12, 24 in which channel the roller 23 is adapted to travel. The shorter series of links 41, 47 has a pivotal connection at 50 with the inwardly and downwardly projecting arm 51, as shown in Fig. 1, the pivot on which arm is adapted to describe an arc of relatively short radius as the pivoted bed section B is swung to either of its two using positions. In the horizontal position of the bed section B the pivot 48 and the pivot 50 are disposed in horizontal planes to either side of the horizontal plane of the supporting pivot 38 for the bed section B, and the pivot 48 lies at a greater distance from the supporting pivot 38 than does the pivot 50. This arrangement means that in swinging the bed section B, a different rate of movement is imparted to the rear portion of bed section A than to its front portion, and hence when the section B is moving forwardly and downwardly through its intermediate range of movement, or inwardly and downwardly through such range, the vertically movable bed section A is tilted from its rear edge portion downwardly. The result is that the mattresses supported on the two bed sections are prevented from being squeezed together or unduly crowded at their edge portions which are adjacent to the pivotal support for the bed section B.

During these movements the guide roller 23 travels downwardly or upwardly, as the case may be, in the channel provided therefore in the rear upright, such roller constituting a sort of pivotal support or fulcrum for the bed section A, holding such section against lateral movement thereon. In order to take full advantage of these movements, the lifting link 40 is preferably shorter than the lifting link 41, and the link 41 is inclined towards the link 40 when the bed is in open position shown in Fig. 5, so that a decided tilting movement is imparted to the bed section A immediately that the pivoted bed section B starts to swing upwardly from the position shown in said figure. These portions of the two lifting links 40, 41 also bring about an upward movement of the rear portion of bed section A and a delay of the upward movement of the forward portion of section A when the pivoted bed section B is swung from its closed position.

It will be seen that owing to the position of pivots 50 and 48 on closing the day bed from the position of Fig. 5, the pivot 50 moves rapidly to the left and acts through link 47 upon the pivot 49 at a point relatively

close to pivot 43 of lever 41 causing an augmented motion of pin 44 at end of lever 41. Pivot 48 on the other hand does not move to the left at all until it is lifted to a point as far above pivot 38 as it was originally below it, and then it moves relatively slowly to the left and acts on lever 40 at the greatest possible distance from its fulcrum, causing a relatively slow movement of lever 40. This shows clearly the reason why a forward, downward tilting of the bed section A is produced, but the tilting is further increased because the front link or lever 41 is inclined toward the link or lever 40 when said bed section is in raised position. As the lever 41 is then inclined, it is obvious that in moving down through the upper range of its pivotal movement, it will move its pin 44 more quickly to a given plane somewhat below the original position of its pin 44 than would be the case were said lever parallel with lever 40.

On referring to Fig. 1 it will be noted that in the closed position of the bed, the bracket 37 rests upon one of the flanges of the front upright 13 so that the downward pull on the pivot 38 by the weight of the bed section A is considerably decreased, if not entirely removed. Also, when the bed is in closed position, the rear edge portion, or rather that portion of the frame section B which is remote from pivot 38, rests upon the rear upright 24. In the closed position of the bed it will be noted that the lifting links 46, 47 act as links for supporting the bed section A, in such position that ample space is provided between the border wires 26, 33 of the two bed sections for containing the mattress for each section, without crowding them.

When the bed is in closed position, the helical spring 56 is under considerable tension which is a great aid in opening the bed section B, the spring 56 having been placed under tension by the lowering of the bed section A. In this position of the bed, the helical springs 53, 54 are in relaxed condition, and when the pivoted bed section B is swung to its outward using position, these springs 53, 54 are placed under considerable tension so that they will act to aid the operator of the bed when the pivoted bed section B is lifted from its outward position. The helical spring 53 may be said to be the main one for assisting in the upward and inward movement of section B, while the helical spring 54 acts as an assistant thereto inasmuch as it exerts its tension on the short connecting link 47. The arrangement and action of the helical springs 53, 54 and 56 is such that they do their work of assistance to the operator so that there is no dead spot in such assistance.

The construction and operation of the operating mechanism described and shown is such that the couch portion 31 of bed section B may have an over all length which is con-

siderably greater than that of the mattress 34, with the incidental and important advantage that when the bed is in closed position, the couch portion 31 will entirely or substantially fill in between the head and foot boards of the bed, or between their upholstered inner surfaces if the boards are upholstered. The arrangement and construction of the operating mechanism is calculated so that it will not interfere with, deface or otherwise injure the extended end portions of couch portion 31. Advantage may be taken of these facts by placing low spring coils within the upholstered end portions of the couch portion 31, so that the extreme ends of the couch will be comfortable to sit upon. Such construction is not illustrated as it is believed unnecessary, nor is there illustration of the fact that the bed spring coils 32 may be formed from double springs, that is to say, a smaller portion of each of such springs constitutes the direct supporting means for the border wire 33 and the mattress, while a larger portion of each of said bed springs constitutes a support for the upholstery of the couch portion 31, the intermediate parts of such springs being carried in well known manner by means of transverse and longitudinal wires supported by the metallic frame of the bed section B.

It is obvious that the present invention may be modified more or less as desired by those skilled in the art and that it would still be within the appended claims.

What I claim as new is,—

35 1. In a bed structure, the combination of a main frame, two bed sections, one of which is movable up or down on the main frame, and the other is pivoted to the main frame, and operating mechanism connecting the bed sections for moving them to collapsed position or to a side by side position, the operating mechanism including a pair of lifting links pivoted at corresponding ends to the main frame and having shiftable connecting means

40 45 at the opposite ends with the upwardly movable section, a connecting link pivotally connected at one end with the shiftable connecting means of one of the lifting links and at the opposite end pivoted to the pivoted bed section at a point away from the pivot of that section, and a link of less length than the aforesaid connecting link, and being at one end pivotally connected with an intermediate portion of the other lifting link and pivoted

50 55 at its opposite end to the pivoted bed section at a point between the pivot of said connecting link with the pivoted bed section and the pivot of that section, whereby a tilting movement may be given to the upwardly movable bed section.

30

2. In a bed structure, the combination of a main frame, two bed sections, one of which is movable up or down on the main frame, and the other is pivoted to the main frame, and operating mechanism connecting the bed sec-

tions for moving them to collapsed position or to a side by side position, the operating mechanism including a pair of lifting links respectively pivoted forwardly and rearwardly on the main frame at one end, and having shiftable connecting means at the opposite ends with the upwardly movable section, a connecting link pivotally connected at one end with the shiftable connecting means of the rearward lifting link and at the opposite end pivoted to the pivoted bed section at a point rearward from the pivot of that section when the bed is closed, and a connecting link of less length than the aforesaid connecting link, and being at one end pivotally connected with an intermediate portion of the forward lifting link and pivoted at its opposite end to the pivoted bed section at a point between the pivot of aforesaid connecting link with the pivoted bed section and the pivot of that section, and the pivot of the pivoted bed section being located, when the bed is closed or open, in a horizontal plane between the horizontal planes of the pivots connecting the two connecting links with the pivoted bed section, whereby a tilting movement may be given to the upwardly movable bed section.

3. In a bed structure, the combination of a main frame, two bed sections, one of which is movable up or down on the main frame, and the other is pivoted to the main frame, and operating mechanism connecting the bed sections for moving them to collapsed position or to a side by side position, the operating mechanism including a pair of lifting links pivoted at corresponding ends to the main frame and having pin-and-slot connecting means at the opposite ends with the upwardly movable section, a connecting link pivotally connected at one end with the pin of one of the lifting links and at the opposite end pivoted to the pivoted bed section at a point away from the pivot of that section, and a link of less length than the aforesaid connecting link, and being at one end pivotally connected with an intermediate portion of the other lifting link and pivoted at its opposite end to the pivoted bed section at a point between the pivot of said connecting link with the pivoted bed section and the pivot of that section, whereby a tilting movement may be given to the upwardly movable bed section. 115

4. In a bed structure, the combination of a main frame, two bed sections, one of which is movable up or down on the main frame, and the other is pivoted to the main frame, and comprises a frame having springs arranged at one side for supporting a mattress, and an upholstered couch portion arranged upon the other side and extended at the end beyond the springs, mattress and the frame therefor, and operating mechanism connecting the bed sections for moving them to collapsed position or to a side by side position, the operating mechanism including a pair

- of lifting links pivoted at corresponding ends to the main frame and having shiftable connecting means at the opposite ends with the upwardly movable section, a connecting link pivotally connected at one end with the shiftable connecting means of one of the lifting links and at the opposite end pivoted inside the frame of the pivoted bed section at a point away from the pivot of that section, and a link of less length than the aforesaid connecting link, and being at one end pivotally connected with an intermediate portion of the other lifting link and pivoted at its opposite end to the frame of the pivoted bed section 70 at a point between the pivot of said connecting link with the pivoted bed section and the pivot of that section, whereby a tilting movement may be given to the upwardly movable bed section.
5. In a bed structure, the combination of a main frame having vertical guides at the rear, two bed sections, one of which is movable up or down on the main frame, and the other is pivoted to the main frame, guide members on the rear of the upwardly movable section and adapted to move on the vertical guides, and operating mechanism connecting the bed sections for moving them to collapsed position or to a side by side position, the operating mechanism including a pair of lifting links pivoted at corresponding ends to the main frame and having shiftable connecting means at the opposite ends with the upwardly movable section, a connecting link pivotally connected at one end with the shiftable connecting means of one of the lifting links and at the opposite end pivoted to the pivoted bed section at a point away from the pivot of that section, and a link of less length than the aforesaid connecting link, and being at one end pivotally connected with an intermediate portion of the other lifting link and pivoted at its opposite end to the pivoted bed section at a point between the pivot of said connecting link with the pivoted bed section and the pivot of that section, whereby a tilting movement may be given to the upwardly movable bed section as the guide members move on the vertical guides.
6. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with the main frame, a sliding connection with the rear portion of the vertically movable bed section and a pivotal connection with an intermediate portion of the pivoted bed section, a rigid short arm on the pivoted section projecting downwardly away from the pivot thereof when the bed is closed, and a relatively short series of links in front of the other series of links in front of the other series, and having a pivotal connection with the main frame, a sliding connection with the front portion of the vertically movable section and a pivotal connection with the short arm, whereby the upwardly movable section may be tilted from its rear downwardly.
7. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with the main frame, a sliding connection with the rear portion of the vertically movable bed section and a pivotal connection with an intermediate portion of the pivoted bed section, a rigid short arm on the pivoted section projecting downwardly away from the pivot thereof when the bed is closed, and a relatively short series of links in front of the other series of links in front of the other series, and having a pivotal connection with the main frame, a sliding connection with the front portion of the vertically movable section and a pivotal connection with the short arm, whereby the upwardly movable section may be tilted from its rear downwardly.
8. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with the main frame, a pin-and-slot connection with the rear portion of the vertically movable bed section and a pivotal connection with an intermediate portion of the pivoted bed section, a rigid short arm on the pivoted section projecting downwardly away from the pivot thereof when the bed is closed, and a relatively short series of links in front of the other series, and having a pivotal connection with the main frame, a pin-and-slot connection with the front portion of the vertically movable section and a pivotal connection with the short arm, and the pivot of the pivoted bed section being located, when the bed is closed or open, in a horizontal plane between the horizontal planes of the pivots connecting the two series of links with the pivoted bed section, whereby the upwardly movable section may be tilted from its rear downwardly.
9. In a bed structure, the combination of a

main frame, two bed sections, one of which is movable up or down on the main frame and the other is pivoted to the main frame, and comprises a frame having springs arranged at one side for supporting a mattress, and an upholstered couch portion arranged upon the other side and extended at the end beyond the springs, mattress and the frame therefor, and operating mechanism connecting the bed sections for moving them to collapsed position or to a side by side position, the operating mechanism including a series of links having a pivotal connection with the main frame, a sliding connection with the rear portion of the vertically movable bed section and a pivotal connection with an intermediate portion of the frame of the pivoted bed section, a rigid short arm on the frame of the pivoted section projecting downwardly away from the pivot thereof when the bed is closed, and a relatively short series of links in front of the other series, and having a pivotal connection with the main frame, a sliding connection with the front portion of the vertically movable section and a pivotal connection with the short arm, whereby the upwardly movable section may be tilted from its rear downwardly.

10. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with the main frame, a sliding connection with the rear portion of the vertically movable bed section and a pivotal connection with an intermediate portion of the pivoted bed section, a tension spring from the main frame to such series of links, a rigid short arm on the pivoted section projecting downwardly away from the pivot thereof when the bed is closed, a relatively short series of links in front of the other series, and having a pivotal connection with the main frame, a sliding connection with the front portion of the vertically movable section and a pivotal connection with the short arm, a tension spring from the main frame to the rigid arm, and an assisting tension spring from the main frame to the relatively short series of links, whereby the upwardly movable section may be tilted from its rear downwardly and ease of operation assured.

11. In a bed structure, the combination of a main frame, two bed sections, each provided with a spring supporting frame, one of which frames is movable up or down on the main frame, and the other is pivoted directly to the main frame, an operating mechanism connecting the frames of the bed sections for moving them to collapsed position

or to a side by side position, the operating mechanism including a connecting link acting at one end upon the frame of the upwardly movable bed section and at the opposite end pivoted to the frame of the pivoted bed section at a point rearward from the pivot of that frame when the bed is closed, and a connecting link which also acts at one end upon the frame of the upwardly movable bed section and is pivoted at its opposite end to the frame of the pivoted bed section at a point between the pivot of the first mentioned connecting link with the frame of the pivoted bed section and the pivot of that frame, and the pivot of the frame of the pivoted bed section being located, when the bed is closed or open, in a horizontal plane between the horizontal planes of the pivots connecting the two connecting links with the frame of the pivoted bed section. 70 75 80 85

12. In a bed structure, the combination of a main frame, two bed sections, one of which is movable up or down on the main frame, and the other is pivoted to the main frame, an operating mechanism connecting the bed sections for moving them to collapsed position or to a side by side position, the operating mechanism including a connecting link acting at one end upon the upwardly movable bed section and at the opposite end pivoted to the pivoted bed section at a point rearward from the pivot of that section when the bed is closed, the ends of such connecting link being deflected toward their pivots, and a connecting link which also acts at one end upon the upwardly movable bed section and is pivoted at its opposite end to the pivoted bed section at a point between the pivot of the first mentioned connecting link with the pivoted bed section and the pivot of that section, and the pivot of the pivoted bed section being located, when the bed is closed or open, in a horizontal plane between the horizontal planes of the pivots connecting the two connecting links with the pivoted bed section. 90 95 100 105 110

13. In a bed structure, the combination of a main frame, two bed sections, one of which is movable up or down on the main frame, and the other is directly pivoted to the main frame, an operating mechanism connecting the bed sections for moving them to collapsed position or to a side by side position, the operating mechanism including a connecting link acting at one end upon the rear portion of the upwardly movable bed section and at the opposite end pivoted to the pivoted bed section at a point rearward from the pivot of that section when the bed is closed, and a shorter connecting link which acts at one end upon the forward portion of the upwardly movable bed section and is pivoted at its opposite end to the pivoted bed section at a point between the pivot of the first mentioned connecting link with the pivoted bed section and the pivot of that section, and the pivot of the

pivoted bed section being located, when the bed is closed or open, in a horizontal plane between the horizontal planes of the pivots connecting the two connecting links with the 5 pivoted bed section.

14. In a bed structure, the combination of a main frame, two bed sections, one of which is movable up or down on the main frame, and the other is provided with a frame directly pivoted to the main frame, an operating mechanism connecting the bed sections for moving them to collapsed position or to a side by side position, the operating mechanism including a connecting link acting at 15 one end upon the rear portion of the upwardly movable bed section and at the opposite end pivoted to the pivoted bed section at a point rearward from the pivot of that section when the bed is closed, the pivots of such link 20 lying in substantially a horizontal plane when the bed is open, and a shorter connecting link which also acts at one end upon the forward portion of the upwardly movable bed section and is pivoted at its opposite end directly 25 to the pivoted bed section at a point which is spaced away from the pivotal connection of the longer connecting link therewith, and which point is over such plane when the bed is open, both links extending downwardly 30 when the bed is closed.

15. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection at one end with the 35 main frame, a shiftable connection at an intermediate point with the rear portion of the vertically movable bed section and a pivotal connection at its other end with an intermediate portion of the pivoted bed section, and a 40 relatively short series of links in front of the other series, and having a pivotal connection at one end with the main frame, a shiftable connection with the front portion of the vertically movable section and a pivotal 45 connection at its other end with the pivoted bed section.

16. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links 55 having a pivotal connection with the main frame, a shiftable connection with the rear portion of the vertically movable bed section and a pivotal connection with an intermediate portion of the pivoted bed section, 60 and a relatively short series of links in front 65

of the other series, and connecting the bed sections with the main frame for relative movements of such sections.

17. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with a front portion of the main frame, a shiftable connection with the front portion of the vertically movable bed section and a pivotal connection with the pivoted bed section, and a relatively long series of links behind the other series, and connecting the bed sections with the main frame for relative movements of such sections. 70 75 80

18. In a bed structure, the combination of a main frame, two bed sections, one of which is movable up or down on the main frame and the other is pivoted to the main frame, and operating mechanism connecting the bed sections for moving them to collapsed position or to a side by side position, the operating mechanism including a series of links having a pivotal connection with the main frame, a shiftable connection with the rear portion of the vertically movable bed section 90 95 and a pivotal connection with an intermediate portion of the pivoted bed section, and a relatively short series of pivoted links in front of the other series, including a link pivoted at the end of the series to the main frame, 100 and extending beyond its next pivot in the series to the front portion of the vertically movable section and having a shiftable connection therewith, and the other end of the short series having a pivotal connection with the pivoted bed section. 105

19. In a bed structure, the combination of a main frame, two bed sections, one of which is movable up or down on the main frame and the other is pivoted directly to the front of the main frame for an arcuate movement thereon around the pivot from closed to open position or the reverse, and operating mechanism connecting the bed sections for moving them to collapsed position or to a side by side position, the operating mechanism including two series of links, each series having a separate pivotal connection from the other with the main frame, and each series having means connecting it with the bed sections for tilting the upwardly movable bed section downwardly with respect to the front of the main frame as such section is arriving at or leaving its upper level. 110 115 120

20. In a bed structure, the combination of a main frame, two bed sections, one of which is movable up or down on the main frame, and the other is pivoted to the main frame, an operating mechanism connecting the bed sections for moving them to collapsed position. 125 130

tion or to a side by side position, the operating mechanism including a pair of lifting links pivoted one in front of the other at corresponding ends to the main frame and

5 the front link being inclined toward the rear link when the upwardly movable bed section is in raised position, and such links having shiftable connecting means at the opposite ends with the upwardly movable sec-

10 posite ends with the upwardly movable section, a connecting link pivotally connected at one end with the rear lifting link and at the opposite end pivoted to the pivoted bed section at a point away from the pivot of that section and a link of the bed section.

15 that section, and a link of less length than the aforesaid connecting link, and being at one end pivotally connected with an intermediate portion of the front lifting link and pivoted at its opposite end to the pivoted bed sec-

20 tion at a point between the pivot of said connecting link with the pivoted bed section and the pivot of that section, whereby a tilting movement may be given to the upwardly movable bed section.

21. In a bed structure, the combination of a main frame, two bed sections, one of which is movable up or down on the main frame, and the other is directly pivoted to the main frame, and operating mechanism connecting the bed sections for moving them to collapsed

30 the bed sections for moving them to collapsed position or to a side by side position, the operating mechanism including a connecting link having a sliding pivot connection at one end with and upon the rear portion of the

35 upwardly movable bed section and at the opposite end pivoted to the pivoted bed section at a point rearward from the pivot of that section when the bed is closed, the pivot connecting the connecting link with the piv-

oted bed section being located in front of the pivot of the pivoted bed section when the bed is open, and, when the bed is open, such link extending from the rear portion of the upwardly movable bed section to a point be-

15 beyond the forward portion of that bed section, the operating mechanism also including lifting links cooperating with the connecting link for imparting a tilting movement to the upwardly movable bed section, and such links

50 upwardly movable bed section, and such links supporting the latter directly from the main frame when it is tilting and in its raised position, one of such links being pivotally connected with the inner end of said connecting link.
